CONTROL HANDLE

William J. Turnbull, Garden City, N. Y., assignor to The Glenn L. Martin Company, Middle River, Md., a corporation of Maryland

Application August 20, 1942, Serial No. 455,464

7 Claims. (Cl. 200—157)

This invention relates to a control handle whereby many operations can be effected. The handle may be used singly, or in pairs mounted on a connecting yoke or spindle. While this type of control has many applications, the problem of immediate concern is the control of power-operated gun turrets.

In high altitude fighting planes, the gunner in the power-operated turret is isolated from the crew of the ship. His job is to aim one or more guns by controlling the elevation of the guns and the train of the turret. He is in communication with the pilot by the intercommunication system. These tasks require many controls, literally at his finger tips. The gunner can be kept warm by means of electrically heated clothes but due to the controls he must operate, his hands must be uncovered. When the gunner has had to operate metal controls with his bare hands at high altitudes and low temperatures, after the excitement of a dog-fight, or any other cause, due to the palms of the hands perspiring, his hands may freeze to the controls.

By this invention a hand grip for a control is provided that affords a natural repose position of the hand of the operator and thereby lessens fatigue. The surface of the hand grip is extended and indented to comfortably accommodate the hand of the operator.

The hand grips of this invention being made of a plastic material, or any base material covered with plastic material, the hands of the operator will not freeze to the grips.

Further objects of the present invention will become more apparent from the description of the accompanying drawings which form a part of the disclosure and wherein like reference numerals refer to like parts.

It is to be understood that certain changes, substitutions, alterations and modifications may be made without departing from the spirit and scope of the appended claims:

Figure 1 is a perspective view of a pair of control handles mounted on a control yoke or spindle which is supported by a pedestal.

Figure 2 shows another form of mounting the control yoke or spindle.

Figure 3 is a sectional view of the hand grip.

Figure 4 is a view of the cover portion with the parts assembled therein.

Figures 5 and 6 show a slightly modified form of the invention.

In Figure 1, the control yoke generally shown as 1, comprises a supporting pedestal 2 and a hori-

zontal member 3, upon the ends of which are mounted a pair of hand grips 4 and 5.

The hand grips are shown in more detail in Figures 3 and 4. Figure 3 shows the hand grip comprising a body member 6 and a cover member 7, preferably of plastic material or any base material covered with plastic. A ferrel 8 is moulded in, or otherwise secured to a body member 6 and is internally threaded, in the preferred form shown, for mounting on the yoke or spindle.

It should be pointed out that the ferrel is inserted in the grip in such a position that the axis of the ferrel intersects the center of pressure of the hand of the operator. The contour of the grip is such that the operator will always grasp the grip in the same manner. Due to pitching and tossing of the air craft, or any vehicle on which the control may be used, the operator may brace himself on the grips to steady himself while using the gun sight. If the center of pressure of the hand of the operator is substantially on the axis of the spindle, the operator may brace or steady himself on the grips without causing inadvertent moving of the guns. In other words, in normal operation and use, there will be no turning moment on the grip, due to the center of pressure coinciding with the axis of the mounting spindle.

The body member and cover member have cavities formed therein for the reception of switches 9, 10 and 11. The switches 9 and 10 are unitary, self-contained switches fitted into the cavities in the body portion and cover portion. These switches can be adapted to any control circuit.

35 The usual uses to which they are put in a power-operated gun turret are, switch 9 in the left-hand grip is a microphone switch on an intercommunication system, whereas switch 9 in the right-hand grip is a speed control switch and switch 10 in each grip is a fire control switch. Switch 11 is also mounted in a cavity formed by the body and cover portions. This switch is a master switch on the circuits of the control switches and, as can be seen from Figure 3, is actuated by the hand 40 of the operator when placed on the grip. Switch 11 is actuated by lever 12, pivoted to the cover member. Lever 12 is urged outwardly of the cover by spring 29.

45 Lever 13 is pivoted at 14 to member 25 and 26 carried by cover 7, and is held in an up position by spring 15. In the up position, the follower 16 on lever 13 rests in the depression 17 of lever 12 causing lever 12 to operate switch 11. When the hand of the operator grasps the grip, the side of 55 the hand moves lever 13 to a down position. Por-

tion 18 of lever 12 acts as a cam surface on which follower 16 rides and causes lever 12 to move inside the grip and close switch 11. If the hand of the operator is removed from the grip, lever 13 is moved upwardly by the spring 15 and the circuit is broken.

Element 18 shown in invisible lines is a reinforcing member in the plastic lever 13. Figure 4 shows the cooperation between control switch 10 and its actuating lever 20. This actuating lever is mounted in a cavity formed between the body portion and cover portion and is pivoted at 21. It should be noted that actuating member 20 is located in the hand grip so that it forms a convenient and natural rest for the index finger of the hand of the operator.

The location and purpose of switch 9 can best be seen in Figure 1. The external surface of the grip is formed with indented portions for the reception of the hand of the operator and indented portion 22 is designed for a thumb rest. Indented portion 23 is located adjacent 22 and forms an alternative position for the thumb of the operator. The control button 24 of switch 9 extends through the surface of the indented portion 23, thus it can be seen that the operator can easily and quickly operate switch 9 by moving his thumb from the normal to the alternative thumb rest.

The operation of the assembly can be followed on Figures 1 and 2. The operator grasps a grip in each hand, in doing so actuates levers 13 and 12, thus closing the master switches of the operating circuits without effort. Twisting the handles in either direction about the horizontal axis of the spindle controls a mechanism to elevate and vary the rate of elevation of the guns, turning the spindle by means of handles or grips in either direction about the vertical axis of the spindle, controls the train and rate of motion in train of the turret.

Member 20 on each hand grip is connected to actuate trigger control mechanism or may be adapted for any other control.

Member 20 on the right hand grip can be adapted for fire control. Switch button 24 on the left hand grip can be adapted to control the intercommunication system or any other similar circuit. Switch button 24 on the right hand grip is adapted for speed control.

It will be seen from the drawings that the hand grip is so designed that its extended surface has extended and indented portions to accommodate the hand of the operator in a comfortable and natural position. The internal cavities of the portions of the grip are adapted to take the switches and actuating members and can readily be formed by a simple moulding operation.

The unitary switches are put in place, indexed by projections on the cavities and corresponding notches in the switches and retained by the cover member which is held by screws 28. The threaded bushings 27 are moulded into the body member 8. The only machine operation is the drilling of the holes for the pivot pins to mount the levers 12 and 13.

Figures 5 and 6 show a modified form of the hand grip for a control having a single control switch 10 actuated by member 20 and a master control switch similar to switch 11 in structure and function. It should be obvious that the number and location of the switches can be varied according to the adaption of the hand grip.

I claim as my invention:

1. A director and control assembly adapted for

a gun turret mounted for movement in azimuth having guns mounted for movement in elevation comprising a pedestal member, a spindle member mounted on said pedestal member for turning movement about the longitudinal axis of the spindle and bodily swinging movement about an axis of said pedestal normal to said spindle axis, the turning movement about said first-named axis adapted to effect the control of the gun in elevation and the bodily swinging movement of the spindle about the second-named axis adapted to effect the control of the motion of the turret in azimuth, a pair of elongated hand grips one fixed to each end of said spindle to effect a turning of the spindle on said first-named axis by a rotation of the hand grips on said axis and to effect a bodily swinging of the spindle about the second-named axis, each of said hand grips being fixed to the spindle near the mid-portion of the hand grips, switch means on each of said grips to position the hands of the operator grasping the grips whereby the axis of the spindle member substantially intersects the line of thrust of the hands of the operator.

2. A director and control assembly comprising a pedestal member a spindle member mounted on said pedestal member for turning movement about the longitudinal axis of said spindle and bodily swinging movement about an axis of said pedestal normal to said spindle axis, the turning movement about said first named axis effecting the control of one motion of the director and the bodily swinging movement of the spindle about the second-named axis effecting the control of another motion of the director, a pair of elongated hand grips one fixed to each end of said spindle to effect a turning of the spindle on said first-named axis by a rotation of the hand grips on said axis and to effect a bodily swinging of the spindle about the second-named axis, each of said hand grips being fixed to the spindle near the mid-portion of the hand grips, switch means on said grips to position the hands of the operator grasping said grips, whereby the axis of the spindle member substantially intersects the line of thrust of the hands of the operator.

3. A director and control assembly comprising a spindle member mounted for turning movement about the longitudinal axis of the spindle and bodily swinging movement about an axis normal to the spindle axis, the turning movement about said first-named axis effecting the control of one motion of the director and the bodily swinging movement of the spindle about the second-named axis effecting the control of another motion of the director, a pair of elongated hand grips one fixed to each end of said spindle to effect a turning of said spindle on said first-named axis by a rotation of the hand grips on said axis and to effect a swinging of said spindle about said second-named axis, each of said hand grips being fixed to the spindle near the mid-portion of the hand grips, switch means on said grips to position the hands of the operator grasping said grips, whereby the axis of the spindle member substantially intersects the line of thrust of the hands of the operator.

4. A director and control assembly comprising a spindle member mounted for turning movement about the longitudinal axis of the spindle and bodily swinging movement about an axis normal to the spindle axis, the turning movement about said first-named axis effecting the control of one motion of the director and

the bodily swinging movement of the spindle about the second-named axis effecting the control of another motion of the director, an elongated hand grip fixed to said spindle to effect a turning of said spindle on said first-named axis by a rotation of the hand grip on said axis and to effect a swinging of said spindle about said second-named axis, said hand grip being fixed to the spindle near the mid-portion of the hand grip, switch means on said grip to position the hand of the operator grasping said grip whereby the axis of the spindle member substantially intersects the line of thrust of the hand of the operator.

5. A moulded plastic hand grip for use in a gun turret director and control assembly comprising a body portion disposed at one side of said grip and said body portion forming at least a part of a front face disposed toward the operator, a mounting ferrel extended from the side of said body portion opposite said cover portion making such an angle with said body portion that said hand grip will be so inclined that it will afford a natural repose position for the hand of the operator, said front face having formed therein an idle thumb rest cavity and a switch cavity, a switch projecting from within the body of the grip into said switch cavity, said two cavities being adjacent each other so that the switch may be easily operated by the thumb of the operator by movement of the thumb from the idle rest cavity into the switch cavity.

6. A moulded plastic hand grip for use in a gun turret director and control assembly com-

- 10 prising a body portion and a cover portion, said cover portion disposed at one side of said grip and said body portion forming at least a part of a front face disposed toward the operator, said front face having formed therein an idle thumb rest cavity and a switch cavity, a switch projecting from within the body of the grip into said switch cavity, said two cavities being adjacent each other so that said switch may be easily operated by the thumb of the operator by movement of the thumb from said idle rest cavity into said switch cavity, a trigger switch projecting from the back face of said body portion, opposite said idle thumb rest cavity, so that when operated by the index finger of the hand of the operator, the thumb of the hand of the operator in the idle thumb rest braces the grip against inadvertent movement as the trigger switch is actuated.
- 15 20 25 30 7. A moulded hand grip for use in a gun turret director and control assembly comprising a body portion and a cover portion, said cover portion disposed at one side of said grip and said body portion forming at least a part of a front face disposed toward the operator, said front face having formed therein an idle thumb rest cavity and a switch cavity, a switch projecting from within the body of the grip into said switch cavity, said two cavities being adjacent each other so that the switch may be easily operated by the thumb of the operator by movement of the thumb from said idle rest cavity into said switch cavity.

WILLIAM J. TURNBULL.
